UNITED STATES PATENT OFFICE.

MARCUS L. MITCHELL, OF ST. LOUIS, MISSOURI, ASSIGNOR TO THE DE LA VERGNE REFRIGERATING MACHINE COMPANY, OF NEW YORK, N. Y.

BUFFER FOR GAS-COMPRESSOR VALVES.

SPECIFICATION forming part of Letters Patent No. 356,597, dated January 25, 1887.

Application filed October 22, 1885. Serial No. 180,678. (No model.)

To all whom it may concern:

Be it known that I, MARCUS L. MITCHELL, of the city of St. Louis, in the State of Missouri, have invented certain new and useful Improvements in Buffers for Gas-Compressor Valves, of which the following is such a full, clear, concise, and exact description as will enable others skilled in the art to which my invention appertains to make and use the same, reference being had to the accompanying drawings, forming part of this specification.

My invention relates more especially to gas-compressors for refrigerating-machines which use a cooling, sealing, and lubricating liquid, forming what is known also as a "liquid piston," and may be adapted to both vertical and horizontal compressors used in such machines, and also to use in connection with gas-compressors for other than refrigerating purposes. In some vertical gas-compressing cylinders heretofore constructed the discharge-valve has been made to lift up into a dome or valve-chamber located above the compressor-cylinder, and into which dome or chamber the compressed gas is discharged by the lifting of this valve during the upward or compression stroke of the compressor-piston. The gas and oil thus discharged into the dome or valve-chamber of the compressor is conducted therewith by a discharge-pipe communicating therewith, and leading to what is termed an "oil-separating tank." The discharge-valve in such compressors, which is preferably cup-shaped, made of metal, and of necessity very large, is also very heavy. If the height to which this valve may be raised or lifted in the dome of the compressor is not limited by some mechanical means, the force exerted upon it by the compressed gas entering the dome, being variable, will at times raise the valve much higher than is really necessary to allow a free passage of the compressed gas and oil, and the weight of the valve would cause it to descend with considerable force, and oftentimes before the end of the discharge-period, in which case it would strike the valve-seat at a time when such seat was not flooded by or submerged in oil, and thus an injury to either the valve or the valve-seat would inevitably ensue. In some gas-compressors for refrigerating-machines the discharge-valve has been

made to work in ways or guides, and the lift of the valve has been limited by projections or stops on such guides; and in some instances the projections for limiting the upward movement of the valve have been made to extend all around the dome or valve-chamber. It was found, however, that when these projections or stops were located low enough to form a sufficiently-small passage for the compressed gas and oil as that its flow into the valve-chamber or dome would be retarded to the extent requisite to cause it to exert the necessary pressure upon the valve to hold it against such projections or stops and keep it from reseating during the discharge-period, the upper edges of the discharge-valve cup soon become burred by being constantly knocked against the stops. In consequence of this continual hammering some portions of the valve would become larger in diameter, and it would eventually refuse to reseat after being lifted by the discharged gas; and not only so, the valve would sometimes break, thus causing delay and annoyance, and not infrequently serious losses to the owner of the machine, who depended upon its continuous and perfect working. Aside from this, the great and disagreeable noise which in such construction was occasioned when the machine was running at a high speed—say fifty or sixty revolutions per minute—was also a serious objection, and, moreover, there was danger of breaking the valve or guide-stops by running the machine to its otherwise full capacity, and it was therefore necessary, in order to insure safety, that the machine should be run at a moderate speed, which of course lessened its daily performance.

To avoid these objections and to prevent the delays and losses already mentioned, as well as to increase the working capacity of the machine, is the object of my invention, which consists in providing a buffer to receive the valve when lifted or forced upward without burring or breaking it, and in addition thereto in providing a cushion which will render noiseless the movement of the valve against the buffer.

In the drawings similar letters represent corresponding parts.

Figure 1 is a central vertical section of a single-acting gas-compressor and dome or

valve-chamber, such as is used in some refrigerating-machines which circulate a cooling, sealing, and lubricating liquid, and showing also a buffer secured within the dome above the discharge-valve, which is provided with a recess or depression corresponding to the head of the buffer. Fig. 2 is a central vertical section through the dome, discharge-valve, diaphragm-plate, and upper part of the compressor-cylinder on a larger scale. In this figure the buffer-head is shown as corresponding to the valve-cup, but the recess in the bottom plate is omitted, the outlets in the upwardly-projecting walls forming the valve-cup being located sufficiently high to cause the valve to retain a portion of the oil, which forms a cushion for the buffer. Fig. 3 is a like view, but shows the buffer as secured within the dome, and also a recess in the bottom plate of the discharge-valve. This figure also shows the under side of the buffer-head concave, and shows the edges of the head beveled and corresponding to the beveled edges of the recess in the bottom plate of the valve.

25 A represents the dome or discharge-valve chamber; B, the buffer, the under side of which is preferably concave, while C represents the diaphragm-plate with the valve-seat c, and E the outlet from the dome for the gas and oil. From this outlet the gas and oil may pass into an oil-separating tank, (not shown,) which in refrigerating-machines is generally interposed between the compressor and a gas-condenser, the latter not appearing in the drawings. In 35 this tank, to which the gas and oil flow from the dome or valve-chamber, the oil is separated from the hot compressed gas.

In all the figures M represents the cup-shaped discharge-valve, and in Figs. 1 and 3 40 m the projecting walls surrounding a receptacle for oil, which I sometimes make within the base or bottom plate of the discharge-valve, and which is preferably but slightly larger than the head of the buffer B, but corresponding 45 to it in shape as near as may be, and into which oil-receptacle the head of the buffer enters when the discharge-valve is lifted.

In each figure m' m' represent openings in the upwardly-projecting walls forming the cup 50 of the discharge-valve, for alternately admitting oil to and discharging it from the cup of the valve M.

In Fig. 1 F represents the compressor-piston; f, the piston-valve, and f' the piston-rod; 55 G, the suction-nozzle or gas-inlet; g, the suction-valve, and H the oil-inlet.

The piston F is actuated in the usual way, and when it moves upward a partial vacuum is created below it, and as the suction-valve g 60 lifts the gas fills the compressor. Upon the downward stroke of the piston a partial vacuum is created above it, the piston-valve f lifts and the suction-valve g closes, and the gas passes through the openings in the piston between the ribs d d to the upper or compression-chamber of the compressor. During this 65 period a certain quantity of oil under a press-

ure above the pressure of the gas entering the compressor is injected into the compressor through the oil-inlet H, either by means of a pump or other device. The piston F, near the end of its downward stroke, dips into the oil in the bottom of the compressor, and a quantity of oil equal to the quantity injected during the downward stroke of the piston also passes through the openings in the piston. Upon the return or upward stroke of the piston F the gas contained in the compression-chamber of the compressor will be compressed to a pressure a little above the pressure obtaining in the dome or discharge-valve chamber A, when the discharge-valve M will lift and be forced against the buffer B, the head of which enters the valve-cup, as shown in Fig. 2, and when the valve M has the recess formed by the walls m (shown in Figs. 1 and 3) the head of the buffer enters such recess. The rapid passage of the compressed gas through the aperture in the diaphragm-plate will prevent the valve M from descending until the moment when the oil which is lying above the piston is being forced through the valve-passage, and the valve will fall upon the oil, which floods the lower portion of the dome A, thus submerging the valve-seat, and consequently 90 the seating of the valve will be noiseless. The oil now contained in the dome flows through the openings m' into the valve and fills its cup up to the lower edge of such openings, and if the recess formed by the walls m be present in the bottom plate of the valve M this recess will also be filled with oil. When the valve M is again lifted toward the buffer B, the head of the buffer will be met by the oil contained in the valve-cup, which it must displace before the valve can strike it, and if a recess be formed in the bottom plate of the valve the buffer-head must also displace the oil contained therein. In either case the valve will be cushioned by the oil as that the seating thereof will be noiseless.

By constructing the discharge-valve so that it will receive and retain a portion of the oil admitted by it to the dome or chamber such oil will always be present when the machine 115 is in operation, and thus a cushion will be presented to the buffer-head before the valve strikes against it, and by means of such cushion I am not only enabled to avoid the noise occasioned by the use of large discharge-valves 120 constructed as heretofore, but all liability of breaking the parts is obviated, and the machine can consequently perform a greater amount of work within a given time, because 125 of the fact that it can be run at a much higher rate of speed.

My invention may be applied to single or double acting compressors using a liquid base, and the oil may be injected into the lower or upper chamber of the compressor, and either 130 during or after the suction-stroke of the piston or during or before the compression-stroke. It may also be applied to horizontal compressors, provided the valves of such compression-

cylinders lift vertically or at right angles to the center line of such compressors.

I may employ differently-shaped buffers, valves, and domes from those described, but in practice I prefer to use metallic cup-shaped valves, bell-shaped domes and buffers, as shown. The lift of the valve may be made adjustable; but having determined the proper lift of valves of every size in compressors using a cooling, sealing, and lubricating liquid I prefer to have the buffer stationary, and thus prevent the use of unnecessary or moving parts in the dome.

Having thus described my invention, what I claim as new, and desire to secure by Letters Patent, is—

1. In a gas-compressor having a dome or chamber, the combination of a buffer secured in such dome or chamber with a discharge-valve adapted to move toward the said buffer, such valve having a recess or depression therein corresponding substantially to the buffer-head, and adapted to receive such buffer-head when the valve moves up to the same, substantially as described.

2. In a gas-compressor having a dome or valve-chamber, the combination of a buffer

located within such dome or chamber with a discharge-valve adapted to hold and retain a portion of the liquid admitted by it to the 30 chamber and to present the retained liquid to the head of the buffer, whereby the valve is prevented from coming in contact with the buffer-head until it has displaced the liquid retained by the valve, substantially as and for 35 the purpose set forth.

3. In a gas-compressor using a cooling, sealing, and lubricating liquid, the combination of a buffer secured within the discharge-valve chamber with a cup-shaped discharge-valve 40 having therein an oil-receptacle corresponding substantially to the shape of the buffer-head and adapted to hold a liquid whereby a cushion for the buffer may be formed of the liquid contained in such receptacle or recess, which is 45 thus made to neutralize or render noiseless the concussion occasioned by the forcing of the valve up to the buffer-head, substantially as described.

MARCUS L. MITCHELL.
